UNITED STATES PATENT OFFICE.

ROBERT F. BRACKE, OF CHICAGO, ILLINOIS, ASSIGNOR, BY MESNE ASSIGNMENTS, TO
CURTIS B. CAMP, TRUSTEE, OF OAK PARK, ILLINOIS.

CARBURETOR.

Application filed November 21, 1921. Serial No. 516,582.

My invention relates to carburetors, and has for its general object the provision of means for feeding fuel from a supply reservoir to a carburetor located above the reservoir. My invention is illustrated in the form for application to a stationary engine, the speed of which is controlled by a governor driven from the engine.

One object of the invention is to provide a carburetor in which an extremely rich mixture is delivered through a small Venturi tube into the main stream of air flowing through the carburetor casing, the structure being such as to substantially compensate for the over-richness at high engine demand which is ordinarily characteristic of a fixed orifice carburetor.

Another object of the invention is to so locate the governor controlled throttle that it assists in bringing about the compensation by constituting a greater restriction to the main induction passage than to the Venturi tube discharge for low engine demands.

A further object of my invention is to provide a carburetor with a fixed main air intake for all engine demands, and in which the fuel is fed to the intake passage through a very small Venturi tube leading from atmosphere into said passage.

A further object of the invention is to provide a nozzle Venturi tube constituting a primary air intake in combination with a fixed secondary intake both together constituting such a restriction to the flow of air that, for the smallest engine demand, the suction at the throat of the nozzle Venturi tube will be at least sufficient to lift fuel a distance equal to the height of the nozzle above the base of the fuel supply tank plus seven times the depth of the main supply tank so that the difference in height of fuel lift will under no conditions be more than fourteen and one-half per cent of the fuel lifting differential.

Still other objects of the invention will appear from the following detailed description.

My invention is illustrated in the accompanying drawing which represents a section through a carburetor, the drawing also illustrating an engine driven governor connected with the carburetor and a low level supply tank.

A main casing 1 provides the induction passage 2 in which a butterfly throttle 3 is located, operated by a rod 4 connected with a governor mechanism 5 driven by the engine,

not shown, which is being supplied with fuel from the carburetor. The entrance to the induction passage 2 is restricted at 6, the size of this opening being fixed as to size, depending upon the cylinder displacement of the engine. 60

For starting purposes, a choke 7 controlled by lever 8 is provided, which in its illustrated position entirely closes the entrance to the induction passage, but when moved to its alternate position affords a free passage for air into the induction passage from the air tube 9, which in practice may connect with the engine crank casing or with some other suitable source of warm air, such as a so-called "exhaust stove." In practice this choke may be set to constitute a slightly greater or less restriction to compensate for differences in fuel quality and to that extent is manually fixed for running conditions at a certain position. 75

Fuel is supplied to the induction passage through a small Venturi tube 10, entering the induction passage at an angle to the flow of air therethrough. This Venturi tube is provided with fuel openings 11 which are in communication with the main supply of fuel in the low level tank 12 by means of a pipe 13, this pipe being preferably provided with a check valve 14, permitting the flow of fuel in one direction only. The external end of the Venturi tube 10 is provided with a cap 15 having a baffle 16 therein to prevent the discharge of fuel from the external end of the Venturi tube by the suction strokes of the engine. 85

In operation the choke 7 is closed and the engine rotated. At this time, the speed of the engine being far below normal, the throttle 3 is in substantially its wide open position. All of the air drawn into the carburetor in starting the engine passes through the Venturi tube 10, creating a high suction at its throat, drawing the fuel from the low level supply tank to the nozzle openings 11, and discharging it in a fine spray into the induction passage 2, whence it is carried to the engine cylinders through the intake manifold, not shown. As soon as the first explosions are obtained, the choke 7 is opened, 95 preferably first to a position somewhat less than full open, but as the engine warms up, the choke is opened to its final position. As the speed of the engine increases, the governor balls cause the rod 4 to be pushed up 100 105 110

wardly partially closing the throttle 3 to hold the engine to a substantially constant predetermined speed.

The suction produced in the induction chamber 2 is substantially the same as that on the engine side of the throttle 3 when the throttle is wide open. Under these conditions, the discharge end of the Venturi tube 10 is subjected to this suction. As the throttle 3 approaches its closed position, the suction on the engine side of the throttle becomes proportionately greater than that on the anterior side of the throttle, but since the discharge end of the venturi 10 communicates with the induction passage at a position where it is subject partly to the suction on the engine side of the throttle 3 and partly to the suction anterior to that throttle, the suction acting upon it will, under all conditions excepting for wide open throttle, be somewhat greater than the suction in the induction passage 2, and will be considerably greater for the substantially closed position of the throttle 3. This arrangement compensates for the tendency of the Venturi tube to deliver a greater proportion of fuel for high air velocities than for low air velocities. This tendency to richness at high velocities is also partially overcome in my structure by the fact that the Venturi tube 10 is made so small that it does not, under any condition of operation, deliver all of the air necessary for the operation of the engine. This results in the Venturi tube delivering at all times a mixture of fuel and air which is over-rich of fuel, the mixture becoming correct only as that part which is delivered through the Venturi tube is co-mingled with that air which comes through the induction passage 2. It is characteristic of a Venturi tube which is feeding a very over-rich mixture that the suction efficiency of the Venturi tube is greatly decreased by a comparatively small increase in fuel flowing from the nozzle openings in the Venturi tube. To make this statement more specific, let it be assumed that a suction at the discharge end of the Venturi tube 10 equivalent to 30" of gasoline in a manometer tube under idling conditions produces a suction of 60" of gasoline in a manometer tube at the nozzle openings 11 in the Venturi tube. If it were not for the rich mixture of fuel and air passing out of the Venturi tube, an increase in suction of 10" at the discharge end of the Venturi tube would result in an increase of substantially 20" at the throat of the Venturi tube. The richness of the mixture of fuel and air, however, prevents the suction at the throat of the Venturi tube from increasing proportionately to the increase in suction at the discharge end, and under the conditions just named, that is, under a change from 30" to 40" of suction at the discharge end, the increase in suction at the throat is substantially from 60" to 75" instead of

from 60" to 80", as might be expected. This results in a partial compensation for the tendency to over-richness at high engine demand.

In the intake passage of four cycle, single cylinder engines, there is often a slight resurgence of air between the suction strokes. This resurgence may be caused by the intake valve being opened slightly after the closure of the exhaust valve at the end of the scavenger stroke, or it may be caused by the intake valve failing to close until after the crank shaft has passed dead center at the end of the intake stroke. In some engines, it may also be caused by the mere flexibility and inertia of the air in the intake passage; the flow of air being suddenly cut off by the closure of the intake valve will be slightly compressed by the inertia of the column of air in the intake passage and will again slightly expand. It may also be caused by the fact that the air when taken into the intake passage is comparatively cool and has an opportunity to become heated during the non-suction period of the engine, the heat expanding the air and causing it to resurge. Any one of these conditions causes a puff of air in an outward direction through the Venturi tube 10 and carries a small amount of fuel out of the carburetor into the atmosphere unless provision is made to retain the fuel. For this purpose, a cap 15 and baffle 16 are provided, the liquid fuel being collected within the cap and being drawn back into the carburetor upon the next inflow of air on the suction stroke.

I have found it to be of extreme importance that the throat of the nozzle Venturi tube and the size of the restriction at the entrance to the induction passage be so small that for the lowest engine demand, the suction produced at the discharge openings in the Venturi tube will be far in excess of the suction necessary for lifting fuel. If the suction at the throat of the nozzle Venturi tube were only great enough to lift fuel from the base of the supply tank, then the change in fuel feeding differential if the tank were filled would be so great that the proportionality of fuel to air would be so greatly disturbed that the mixture would be very much over-rich. I have found by experimentation that a degree of over-richness which is not materially harmful is obtained when the suction at the nozzle openings in the Venturi tube is equal to the actual maximum fuel lift plus at least seven times the possible variation in fuel head in the main tank. In other words, I have discovered by experimentation that the fuel feeding differential on each side of the nozzle restriction must be at least seven times as great as the possible change in the lift on the tank side of the nozzle restriction. I believe that I am the first to have discovered that a suction greatly in excess of the necessary suction for lifting fuel to the nozzle

avoids the difficulty which has been heretofore experienced from change in fuel level in the supply tank,

Although I have shown and described my invention with respect to certain details of construction, it should be understood that modifications may be made without departing from the spirit or scope of my invention.

What I claim is:

- 10 1. In a carburetor, the combination with an induction passage having a secondary air intake opening manually fixed as to size, of a choke for said intake, a Venturi tube extending from atmosphere and discharging into said induction passage, a low level supply tank, a pipe connecting the low level supply tank with discharge openings at the throat of said Venturi tube, the fixed openings into the induction passage and at the throat of 20 the Venturi tube being so small that the suction produced at the fuel openings in the Venturi tube at the smallest engine demand will be at least sufficient to lift fuel from the base of the low level supply tank plus a distance 25 seven times as great as the possible variation in fuel level in the supply tank, whereby not more than fourteen and one-third percent change in fuel feeding differential will result from a change of fuel level from the substantially empty to the substantially full condition of the supply tank.
  2. In a carburetor provided with a main air induction passage having an inlet opening admitting the greater portion of the air
- to the engine served by the carburetor, a small 35 Venturi tube having one end subjected to the depression within said induction passage between said inlet opening and the engine and having the other end exposed to atmospheric pressure, a fuel discharge port at the throat 40 of said small Venturi tube, a low level source of fuel supply in which the level of fuel varies through a wide range between the full and the empty conditions of the fuel tank, a conduit leading from said fuel tank directly 45 to the nozzle opening in said small Venturi tube, the size and proportions of the air orifice through the Venturi tube and that through said inlet opening, being such that during the least fuel mixture demand of the 50 engine to which the carburetor is attached, the suction at the throat of the Venturi tube and available for lifting the fuel from the low level source of supply to the carburetor and discharging it into the air passing through 55 the Venturi tube is equivalent to that necessary to actually lift the fuel plus at least enough to lift the fuel seven times the height of the variation in fuel level from lowest to highest levels in the main fuel supply tank 60 whereby variations in fuel level in the main supply tank will not materially alter the power output of the engine to which the carburetor is attached.

In witness whereof, I hereunto subscribe 65 my name this 22nd day of October, 1921.

ROBERT F. BRACKE
